HOOK JAW WIRE CONNECTOR

Langdon S. Barron, Sr., St. Louis, Mo., assignor
of one-half to James A. Weaver, Jr., St. Louis,
Mo.

Application July 5, 1939, Serial No. 282,855

6 Claims. (Cl. 24—263)

This invention pertains to wire connectors, as commonly used in electrical installations for connecting tap or service lines to the main lines, or for any similar purpose.

5 An important object of the invention is to provide in simple, practical and unitary form, a connector including an apertured base or wire support or carrier having a lower jaw projecting laterally at one margin of the elongated 10 aperture, a hooked upper jaw aligned over the lower jaw and rockingly supported upon a threaded stem, leg or bolt passed freely down through the aperture of the base and secured by a nut upon the lower protruded end of the 15 stem, the upper margin of the base being cut angularly away back of the upper movable jaw, whereby this jaw may be raised and rocked rearwardly for inserting wires between the jaws, the latter being then drawn together upon the wires 20 by turning up the nut.

Another object is to provide a wire connector comprising a lower base member having an ovate and downwardly flaring aperture therethrough, the upper margin thereof being beveled off at 25 one end of the aperture, the opposite end margin being widened and a relatively large, trough-like or V-shaped jaw being formed transversely therein, a hooked and flattened upper jaw on a threaded stem passed freely down through the 30 base aperture and secured by a nut, the back and shank of the upper jaw being widened on its own plane for holding the upper jaw in alignment over the lower jaw, there being relatively small trough-like or inverted V-shaped projections extended laterally from the bight of the hooked upper jaw adapted to seat within the larger V-shaped lower jaw for engaging relatively small wires, the upper jaw being thus adapted when raised to rock backwards in the 35 base aperture for admitting wires between the jaws.

Another object is to provide in combination with the form of connector above, referred to, a nut for the threaded stem of the upper jaw, said 40 nut having a loop pendently secured thereto for facilitating the use of the connector upon live wires.

The foregoing as well as certain other objects and advantages are secured through the preferred embodiment of the invention and constituent structural features shown in the drawing as a part of the specification, and wherein:

Figure 1 is a side elevation of the connector with two wires locked therein, the wires being 45 shown in section. The nut of this assembly is

shown with a pendent loop for facilitating use upon live wires by means of an insulated tool.

Figure 2 is a frontal elevation of an assembly similar to that of Figure 1, the pendent loop however being omitted.

Figure 3 is a rear elevation of the assembly of Figure 2.

Figure 4 is a top view of the assembly of Figure 2.

Figure 5 is a side elevation of the connector 10 alone, the upper jaw being drawn up and rocked back from the lower jaw, as for the reception of wires.

Figure 6 is a top view of the assembly of Figure 5.

Figure 7 is a sectional elevation of the base member.

Figure 8 is a perspective detail of the upper hooked jaw, stem, and nut and washer thereon.

Figure 9 is a front view of the elements shown 20 in Figure 8.

In carrying out this invention I provide a somewhat elongated base member or wire support 5, having an ovate, longitudinally disposed aperture 6 formed therethrough at one end, this 25 aperture being flared downwardly and forwardly on its long axis, the side walls of the aperture being parallel. This construction leaves a relatively wide margin at the opposite end of the aperture and which is not rounded off at its 30 outer face, and a wide, beveled groove or guide way 7 is formed centrally down over this outer face. A relatively large, trough-like or V-shaped wire engaging jaw 8 is formed transversely on the upper side of this wider margin, 35 the same overlying the forwardly flared under end of the aperture 6 and cutting into the adjacent end of the ovate aperture 6 at the upper side thereof and leaving at either side the four upstanding points 9 demarking the jaw 8. The 40 upper margins of the aperture 6 are beveled off downwardly from the inner points 9 rearwardly, as shown at 10.

A flattened and hooked upper jaw 12 supported integrally upon a threaded stem or bolt 13 is 45 provided, the stem being freely passed down through the aperture 6, where it is retained operatively in place by the flattened shank portions 12a of the jaw playing freely into the aperture, and by a nut 14 threaded upon the protruded 50 lower end of the stem 13, a washer 15 being interposed if desired. A pendent loop 16 may be secured to the nut 14 for facilitating application of the connector to a live wire. Relatively small, trough-like or inverted V-shaped projec- 55

tions or lugs 18 are integrally formed with and extended laterally from the bight of the hooked upper jaw 12 and are adapted to seat within the trough of the larger V-shaped lower jaw 8 for 5 engaging relatively small wires and so that the two jaws may be accurately and closely drawn together.

With the described construction of the elements, the upper jaw 12 and stem 13, (the nut 10 14 being retracted or lowered upon the stem or or bolt) may be elevated through the aperture 6, and rocked rearwardly as shown in Figure 5, thus fully opening the two jaws for the reception of the wires 19 and 20. After the wires are 15 inserted the upper jaw is dropped, and the downturned hook or nose 12b of the jaw automatically falls into the guide groove 7, and the outer upstanding points 9 of the lower jaw, thereby holding the upper jaw against lateral displacement.

It is to be noted that the upwardly extended opening 12c of the upper jaw is inclined rearwardly into the flattened head of the jaw, so that a preponderant mass of this jaw lies rearward of the long axis of the stem 13. Consequently as the stem is pushed up through the aperture 6, the jaw 12 automatically rocks or falls rearward into the outer end of this ovate aperture, thus fully opening the jaws to the 20 wires, and exposing the lower jaw so that the wires may be placed directly thereon. The stem 13 being then released, the upper jaw automatically drops down over the wires with the nose 12b automatically falling into the groove 7. The 25 nut 14 is then turned up tightly for completing the joint. Owing to the elongated ovate aperture 6 and the flattened structure of the shank of the upper jaw 12, which plays into this aperture, the elements and jaws are automatically held in proper and operative alignment.

For use on dead wires the loop 16 would be omitted and by taking the connector between thumb and forefinger of one hand and using another finger of the hand to push the stem upward, the upper jaw as it rises, automatically falls back, as above stated. For use on live wires the looped form of nut may be used, and a small insulated rod (not shown) may be passed through the loop for turning up the nut.

It is thought that the construction, use and operation of the device will be fully understood from the above description. The connector described is simple, compact, efficient, its elements unitarily assembled so as not to become separated or lost, and it may be quickly and readily manipulated by the fingers of one hand only.

While a specific embodiment of the invention is here described and shown, various structural changes may be made therein as found desirable, and within the scope of the claims.

I claim:

1. A wire connector comprising a base member having a jaw formed on one margin and an elongate aperture formed through the member

with its long axis directed toward the jaw, a threaded stem passed freely through the aperture of the base, a flattened, hooked upper jaw on the threaded stem aligned above the lower jaw, the said upper jaw having flattened shank 5 portions adapted to freely engage the elongate base aperture for operatively aligning the jaws, and a nut on the protruded lower end of the threaded stem.

2. A wire connector comprising an elongate 10 base having a transverse jaw on one end and an ovate aperture formed through the base with its long axis extended perpendicularly adjacent the jaw, said aperture flaring downwardly on its long axis and forwardly under the jaw, a 15 threaded stem passed freely through the aperture of the base, a flattened, hooked upper jaw on the threaded stem aligned over the lower jaw, the said upper jaw having flattened shank parts 20 freely engaging the ovate base aperture for mutual automatic alignment as the jaws are closed together, the preponderant mass of the upper jaw being disposed rearwardly of the threaded stem, whereby the upper jaw automatically falls backward as raised, and a nut on the 25 lower end of the stem protruded through the apertured base.

3. A wire connector comprising an elongate base having an ovate aperture formed therethrough and disposed towards one end thereof, 30 leaving a wider rectilinear margin at the other end, a lower jaw formed transversely on this wider margin, a threaded stem passed freely through the base aperture with a nut on the lower end thereof, a flattened, hook-like upper jaw at the upper end of the stem, the same having flattened shank parts and inverted trough-like projections extended laterally from the upper bight portion aligned and adapted to co-act with the lower jaw, the flattened shank 40 parts of the upper jaw freely engaging the ovate base aperture as the jaws are closed together for holding the parts in operative alignment, the preponderant mass of the upper jaw disposed rearwardly for causing this jaw to automatically fall back as raised.

4. In a structure as defined in claim 3, with the ovate aperture of the base flared downwardly and forwardly beneath the lower jaw for accommodating the stem of the upper jaw as 50 the latter is rocked rearwardly through the aperture.

5. In a structure as defined in claim 3, with the upper side and rear margins of the ovate aperture of the base beveled off for accommodating the stem of the upper jaw as the latter is rocked rearwardly.

6. In a structure as defined in claim 3, with the outer forward face of the base member formed with a medial guide-groove for engaging 60 the hook of the upper jaw and preventing lateral movement thereof.

LANGDON S. BARRON, SR.
